William G. Wood, Douglassville, Pa., assignor to The
Electric Storage Battery Company, Philadelphia, Pa.

Filed Sept. 3, 1965, Ser. No. 86,822

Term of patent 14 years

(Cl. D57—1)

Fig.1.

Fig.2.

Fig.3.

FIG. 1 is a front, elevational view of a pair of welding goggles, showing my new design;

FIG. 2 is a side view; and

FIG. 3 is a top view thereof.

The headband is shown broken away in FIGS. 2 and 3 for convenience of illustration.

The side not shown, is substantially the same as the side shown.

This application is a continuation-in-part of my co-pending application Serial No. D.72,884, filed December 17, 1962, now abandoned.

I claim:

The ornamental design for a pair of welding goggles, substantially as shown and described.
